UNITED STATES PATENT OFFICE.

ALFRED HUTTON AND JOHN M. MAHONEY, OF SCHENECTADY, NEW YORK.

OIL-BURNING APPLIANCE FOR FURNACES.

1,360,641.

Specification of Letters Patent.

Patented Nov. 30, 1920.

Application filed March 29, 1920. Serial No. 369,627.

To all whom it may concern:

Be it known that we, ALFRED HUTTON and JOHN M. MAHONEY, both of Schenectady, in the county of Schenectady and State 5 of New York, have jointly invented a certain new and useful Improvement in Oil-Burning Appliances for Furnaces, of which improvement the following is a specification.

Our invention relates to means for effecting 10 the combustion of hydrocarbon fluids in steam boiler and other heating furnaces, and its object is to simplify and economize the construction, and promote the effective operation, of appliances for this purpose, by 15 the provision of a novel combination of means for heating oil, superheating steam by which it is atomized, and controlling the supply of oil and steam, whereby compactness and facility of application are materially attained, and the use of separate heating 20 and atomizing lines is avoided.

The improvement claimed is hereinafter fully set forth.

In the accompanying drawings: Figure 1 25 is a vertical longitudinal central section, through a locomotive fire-box, illustrating an application of our invention; Fig. 2, a horizontal section; Fig. 3, a half rear view of the back head of the fire-box; Fig. 4 a 30 plan view, on a larger scale, of the oil heater; Fig. 5, a plan view of the breaker plate; Fig. 6, a partial transverse section, on a further enlarged scale, through the same; Fig. 6^a, a side view; Fig. 7, a trans- 35 verse section through the heater, on the line *a a* of Fig. 4; Fig. 8, a view, partly in end elevation, of the same, and partly in trans- 40 verse section, on the line *b b* of Fig. 9; Fig. 9, a longitudinal section, on the line *c c* 45 of Fig. 4; Figs. 10 and 11, transverse sections, on the lines *b b* and *d d*, respectively, of Fig. 9; Fig. 12, a longitudinal central section, through the oil and steam controlling valve; Figs. 13 and 14, side views, in 50 elevation, taken at an angle of 45 degrees one to the other, of the same; Fig. 15, an end view; Figs. 16 and 17, transverse sections, on the lines *e e* and *f f*, respectively, of Fig. 12; and Figs. 18, 19 and 20, trans- 55 verse sections, illustrating different adjustments of the valve, the upper halves of the figures being on the line *f f* of Fig. 12, and the lower halves on the line *e e* thereof.

Our invention is herein exemplified as 55 applied in a locomotive firebox of the present standard medium width type, but, as

will appear upon a consideration of its essential structure, and operative features, it is not limited in application to this, or any other, type of steam boiler furnaces, being 60 adapted for use in connection with heating furnaces of various other descriptions. In the instance herein shown, the inside fire box, 1, is of the usual form, and is surrounded by water spaces, 3, which are closed 65 at bottom by a mud ring, 4, as in ordinary locomotive practice. The outside firebox, 5, is connected to the waist, 5^a, of the boiler, through which a plurality of fire tubes, 5^b, extend to the smoke box. 70

In the practice of our invention, referring descriptively to the specific embodiment thereof which is herein exemplified, the inside firebox, 1, is closed at bottom, for the major portion of its length, by a sheet or 75 plate metal casing, 6, which corresponds substantially, in general relation to the firebox, with the ordinary ash pans of steam boiler furnaces in which solid fuel is used, and will be herein termed the "bottom pan". This 80 casing is suitably secured to, and supported by the mud ring, 4, and the space between its forward end and the front water wall of the firebox, is bridged over, and closed by a plate, 7, on which there is set a fire brick 85 floor, 7^a. The lower portions of the sheets of the inside firebox are faced with a fire brick lining, 8, and a similar lining, 8^a, may also be fitted in the bottom pan, 6. Air for supporting combustion is admitted to the 90 bottom pan, through a draft passage, 6^a in its front, which may be closed by a suitable damper.

An oil heater, 9, preferably of cylindrical form, is suspended below the fire brick floor, 95 7, said heater extending transversely to the firebox and having end lugs, 9^a, on its top, through which it is detachably connected, by bolts, to the plate, 7, which is, in turn, secured to the front member of the mud ring, 100 105 4. As shown in Figs. 7 to 11, inclusive, the interior of the heater, 9, is divided into a central cylindrical oil chamber, 9^b, and a surrounding annular steam chamber, 9^c, the oil chamber having a central partition, 9^c, 105 extending over slightly one-half its length, and being open at its end adjacent to one end of the heater shell. The function of the partition, 9^c, is to effect a return traverse of the oil admitted to the heater casing, 110 from one end to the middle thereof, before passing to the burner. A lateral oil de-

livery conduit, 9^e, leads out of the middle of the oil chamber, 9^b, and an adjoining steam delivery conduit, 9^h, leads out of the steam chamber, 9^e, both the conduits, 9^e and 9^h, being governed by a single controlling valve which will be presently described.

A steam supply pipe, 10, leading from any convenient location of connection to the steam space of the boiler, and controlled by 10 a valve, 10^a, within convenient reach of the operator, leads past the bottom pan, 6, to a steam superheater, 11, which, in this instance, is shown as a continuation of the pipe line, 10, in a plurality of return bends, fitted 15 in the fire brick floor, 7. The delivery end of the superheater section, 11, of the pipe line, 10, is connected to one end of the steam chamber, 9^e, of the heater, 9.

The oil which is used as fuel for the fire- 20 box, is contained in a suitably located supply tank, (not shown), from which it passes, through an oil supply pipe, 13, controlled by a valve, 13^a, to the oil chamber, 9^b, of the heater, within which it traverses 25 throughout the entire length of the chamber, and returns through about half the length thereof, being reversed in direction by the partition, 9^c. In this traverse of the oil through the heater, it is heated by the sur- 30 rounding current of steam in the annular steam chamber, 9^e, the steam having been previously superheated in its passage through the superheater section, 11.

The oil delivery conduit, 9^g, and steam de- 35 livery conduit, 9^h, lead into a valve casing, 12^a, cast integral with the heater, in which casing there is fitted a manually operable controlling valve, 12, by which both of said 40 passages are governed. The controlling valve, which, in the instance exemplified, is of the plug cock type, is held to its conically bored seat in the casing, 12^a, by a spring, 12^b, abutting on the larger end of the valve and on the cap, 12^c, of the valve 45 casing, and is actuated by proper movements of an operating shaft, 14, journaled adjacent to the firebox, and carrying, on its upper end, a lever handle, 14^a. An arm, 14^b, on the lower end of the shaft, 14, is coupled, 50 by a rod, 14^c, to an arm, 14^d, on one end of a shaft, 14^e, the opposite end of which shaft engages a squared stem, 12^d, on the smaller end of the controlling valve.

A transverse oil port, 12^e, of sufficient sec- 55 tional area to afford full delivery from the oil port, 9^g, is formed in the controlling valve, said port having a graduallying inlet groove, 12^f, of triangular section, extending through it, and a transverse steam port, 12^g, 60 of sufficient sectional area to afford full delivery from the steam port, 9^h, extends through the controlling valve, adjacent to the oil port, 12^e. The steam port, 12^g, is disposed at an angle of substantially 45 degrees to the oil port, 12^e, and, as most clearly

shown in Fig. 16, is outwardly inclined, in opposite directions, from the axial line of the valve, so that the body of the valve surrounding it presents two oppositely located conduit closing members, 12^h, 12ⁱ, in the 70 form, in transverse section, of sectors. An oil discharge conduit, 9ⁱ, and a steam discharge conduit, 9^k, controlled by the positions of the valve ports, 12^a and 12^g, respectively, lead from the valve casing to a 75 burner outlet, or atomizer, 15, the area of opening of which may be varied by an adjustable cap plate, 15^a, the conduit, 9ⁱ, communicating with the conduit, 9^k, before reaching the atomizer, through a plurality 80 of perforations, 16^a, in a breaker plate, 16, fitting in a lateral extension of the valve casing, and insertible in and from position, through an opening closed by a removable cap, 16^b. The function of the breaker plate 85 is to divide the oil into a plurality of small streams, thereby increasing the surface of the oil, which is exposed to the action of the current of steam, and correspondingly fa- 90 cilitating the atomizing operation.

It will be seen that the construction of the controlling valve, as above described, is such that the port admitting steam to the atomizer is opened before the port which admits oil, and is closed after the closure of the latter port, both operations being effected by the movement of a single operating handle. In the ordinary constructions, the supply of oil and of steam to the atomizer is controlled by separate and independently operable valves, and, through inadvertence, the oil supply valve may be opened before the steam supply valve, with the result of causing an explosion by the contact of the oil with the hot firebox. The 100 provision of the graduated inlet opening in the oil supply port, enables the supply to be restricted to as small an amount as desired, and renders it possible to maintain a pilot flame for ignition purposes. The steam 105 which is supplied to, and circulates continuously through, the heater, during operation, being previously passed through a superheating section of the supply line, and being consequently dried out and superheated before entering the heater, a higher degree of 110 heat is imparted to the oil, and the intensity of the flame at the burner is consequently increased.

In prior and existing practice, in oil burning appliances for locomotive boilers, the oil is usually conducted from a supply tank, on the tender, to a burner located near the forward end of the firebox, a portion of the oil supply pipe being inclosed in a heating 125 jacket which receives boiler steam. There is no circulation of steam in the jacket, and no steam outlet from it, a "dead line" being thus formed. There is generally a considerable length of pipe between the heat- 130

ing jacket and the burner, and as this is not usually insulated, a substantial amount of the heat imparted to the oil is lost in the passage of the oil from the heater to the burner. While the length of the unprotected pipe is made as short as possible, the loss referred to is always experienced, to a greater or less degree. Another objectionable feature found in present systems, is the 10 location of the firing valve in the pipe line between the heater and burner, and as near the burner as possible. When the locomotive is pulling into a station, the firing valve is closed, and the oil in the pipe between 15 the valve and burner, seeps out through the atomizer into the firebox, and smoulders therein, causing considerable smoke.

The objections above noted are fully obviated in the practice of our invention, the 20 structural features of which, as will be recognized by those familiar with oil burning appliances, are inexpensive, and readily applicable in connection with fireboxes of the present standard forms. It will, further, be obvious that while our invention is more particularly designed for application in connection with locomotive fireboxes, and has, for the purpose of illustration, been so exemplified herein, it may, without variation from its essential structural and operative features, be used with heating furnaces of other types, whether those of steam boilers or other heat generating structures.

We claim as our invention and desire to 35 secure by Letters Patent:

1. In a hydrocarbon burning apparatus for furnaces, the combination of an oil heater comprising separated oil and steam chambers; an oil supply conduit, leading 40 into the oil chamber thereof; a steam supply conduit, leading into the steam chamber; an oil atomizer; an oil delivery conduit and a steam delivery conduit, leading, respectively, from the oil and the steam chamber to the atomizer; and a controlling valve, interposed between the heater and atomizer and governing the steam and oil delivery conduits.

2. In a hydrocarbon burning apparatus 50 for furnaces, the combination of an oil heater, comprising separated oil and steam chambers; an oil supply conduit, leading into the oil chamber thereof; a steam supply conduit, leading into the steam chamber; an oil atomizer; an oil delivery conduit, and a steam delivery conduit, leading, respectively, from the oil and the steam chamber to the atomizer; and a controlling valve, interposed between the heater and atomizer, 55 and independently and successively governing the steam and the oil delivery conduits.

3. In a hydrocarbon burning apparatus 60 for furnaces, the combination of an oil heater comprising separated oil and steam chambers; an oil supply conduit leading

into the oil chamber thereof; a steam supply conduit leading into the steam chamber; a steam superheater, in the line of the steam supply conduit; an oil atomizer; an oil delivery conduit and a steam delivery conduit, 70 leading, respectively, from the oil and the steam chamber to the atomizer; and a controlling valve, interposed between the heater and atomizer and governing the steam and oil delivery conduits. 75

4. In a hydrocarbon burning apparatus for furnaces, the combination of an oil heater, comprising an inner oil chamber and a separated outer steam chamber; an oil supply conduit leading into the oil chamber; a 80 steam supply conduit leading into the steam chamber; an oil atomizer; an oil delivery conduit and a steam delivery conduit, leading, respectively, from the oil and the steam chamber to the atomizer; and a controlling 85 valve, interposed between the heater and atomizer and governing the steam and oil delivery conduits.

5. In a hydrocarbon burning apparatus for furnaces, the combination of an oil 90 heater, comprising an inner oil chamber; a separated outer chamber, and a return flow partition extending throughout a portion of the length of the oil chamber; an oil supply conduit leading into the oil chamber; a 95 steam supply conduit leading into the steam chamber; an oil atomizer; an oil delivery conduit and a steam delivery conduit, leading, respectively, from the oil and the steam chamber to the atomizer; and a controlling 100 valve, interposed between the heater and atomizer and governing the steam and oil delivery conduits.

6. In a hydrocarbon burning apparatus, the combination, with a furnace, of an oil 105 heater comprising separated oil and steam chambers; an oil supply conduit, leading into the oil chamber thereof; a steam supply conduit, leading into the steam chamber; a steam superheater, in the line of the steam 110 supply conduit, and located in position to be heated by the furnace; an oil atomizer; conduits for steam and oil from the chambers of the heater to the atomizer; and a controlling valve governing said conduits. 115

7. In a hydrocarbon burning apparatus for furnaces, an oil heater comprising, in an integral casting, a body or shell having outer supporting flanges, an inner shell, dividing the body into an inner oil chamber 120 and an annular outer steam chamber, and a controlling valve casing, communicating, by separate passages, with the steam and the oil chamber.

8. In a hydrocarbon burning apparatus 125 for furnaces, an oil heater comprising, in an integral casting, a body or shell having outer supporting flanges, an inner shell, dividing the body into an inner oil chamber and an annular outer steam chamber, a con- 130

4
trolling valve casing, communicating, by separate conduits, with the steam and the oil chamber, and a lateral extension projecting from the controlling valve casing and having conduits, extending therefrom to a burner outlet at its end.

9. In a hydrocarbon burning apparatus for furnaces, the combination of a source of steam supply; a source of oil supply; an oil atomizer; conduits, leading from said supply sources to the atomizer; and a controlling valve, having an oil supply port governing the oil conduit, and a steam supply governing port, having its middle plane inclined at an angle to that of the oil supply port, and having oppositely projecting conduit closing members interposed between its ends.

10. In a hydrocarbon burning apparatus for furnaces, the combination of a source of steam supply; a source of oil supply; an oil atomizer; conduits, leading from said supply sources to the atomizer; and a controlling valve, having an oil supply port govern-

ing the oil conduit and provided with a 25 graduating inlet groove of angular section, and a steam supply governing port, having its middle plane inclined at an angle to that of the oil supply port, and having oppositely projecting conduit closing members inter- 30 posed between its ends.

11. In a hydrocarbon burning apparatus for furnaces, the combination of a source of steam supply; a source of oil supply; an oil atomizer; conduits, leading from said supply sources to the atomizer; a controlling valve independently governing said conduits; and a perforated breaker plate, establishing constant communication of the oil conduit and the steam conduit, and inter- 40 posed between the controlling valve and the atomizer.
